UNITED STATES PATENT OFFICE

112,734

DESIGN FOR AN EMBROIDERED TEXTILE FABRIC OR SIMILAR ARTICLE

Gotel Canelstein, New York, N. Y.

Application November 26, 1938, Serial No. 81,404

Term of patent 3½ years

To all whom it may concern:

Be it known that I, Gotel Canelstein, a citizen of the United States and residing in Manhattan, in the city, county, and State of New York, have invented a new, original, and ornamental Design for an Embroidered Textile Fabric or Similar Article, of which the following is a specification, reference being had to the accompanying drawing, forming part thereof, wherein the figure is a plan view of an embroidered textile fabric or similar article showing my new design.

I claim:

The ornamental design for an embroidered fabric textile or similar article, substantially as shown.

GOTEL CANELSTEIN.
